(57) CLAIM

The ornamental design for a hair hat, as shown and described.

DESCRIPTION

Applicant claims the benefit of U.S. Pat. No. Des. 411,577, and Design patent application Ser. No. 29/105,876 now abandoned.

FIG. 1 is a front perspective view of a hair hat, showing my new design;

FIG. 2 is a perspective view showing the rear, top, and left side thereof; and,

FIG. 3 is a top plan view thereof, the bottom view contains no ornamental design.
